UNITED STATES PATENT OFFICE.

ERNST HOTZ, OF HATTERSHEIM-ON-THE-MAIN, AND VALENTIN LANZ, OF HOCHST-ON-THE-MAIN, GERMANY, ASSIGNORS TO GRASSELLI DYESTUFF CORPORATION, OF NEW YORK, N. Y., A CORPORATION OF DELAWARE.

PROCESS OF PREPARING 2-AMINONAPHTHALENE-3-CARBOXYLIC ACID.

No Drawing. Application filed December 16, 1927, Serial No. 240,627, and in Germany December 17, 1926.

This invention relates to a process of preparing 2-aminonaphthalene-3-carboxylic acid.

We have found that 2-aminonaphthalene-3-carboxylic acid of the formula:

- 10 is obtained from 2-hydroxynaphthalene-3-carboxylic acid and ammonia with a yield of about 90 per cent of the theory and in an easy and practical manner by subjecting the products of reaction to the action of a bivalent iron compound in such a manner that a complex iron compound, insoluble in water and ammonia, is formed, and thereafter decomposing the complex iron compound into 2-aminonaphthalene-3-carboxylic acid free from iron. 15 The formation of this new insoluble iron compound not only facilitates the separation of the 2-aminonaphthalene-3-carboxylic acid from the reaction mixture but even promotes the formation of the 2-aminonaphthalene-3-carboxylic acid, the equilibrium of the reaction being always displaced in favor of the insoluble iron compound and the finished aminonaphthalene carboxylic acid being protected against its destruction by any secondary 20 influences.

The insoluble iron compound is formed in an extraordinarily easy manner. The other metals of the iron group, i. e. nickel and cobalt, behave in a similar manner as iron, 25 whereas the other bivalent metals such as zinc, calcium, magnesium and copper give no compound corresponding to the above-mentioned new insoluble iron compound.

The simplest way to introduce the iron required for the reaction is to add it to the reaction liquid in the form of a ferrous salt, for instance ferrous chloride or ferrous sulfate, whereby there is at once formed a colloidal precipitate of ferrous hydroxide which is capable of further participating in the reaction. 30 It is also possible to add directly colloid ferrous hydroxide.

Obviously the same iron compound, but one of a lighter coloration, is obtained by 35 simply adding metallic iron and ammonium chloride or sodium chloride, or another chlo-

ride which attacks the iron under the existing conditions in an ammoniacal medium with evolution of hydrogen gas. Like the chlorides, soluble salts with other anions for instance ammonium carbonate or ammonium sulfate will act in the same manner. The chlorides act, however, most energetically with being attended by the least secondary reactions. The formation of the iron compound depends on the presence of bivalent iron. The metallic iron may be used in the form of iron turnings (filings or borings) or iron powder. The tendency of forming the new, hitherto not yet described iron compound is so strong that in the presence of chlorine-ions if no iron is added thereto the iron compound is formed at the cost of the iron of the wall of the autoclave. The corrosion of the iron by the said salts in the presence of ammonia is enormously increased by the presence of hydroxynaphthalene-carboxylic acid or aminonaphthalene carboxylic acid which are thereby transformed into the insoluble iron compound. In practice, when 40 working with an iron autoclave, it is necessary to avoid the addition of other chloride than those of iron and to add a sufficient quantity of iron in the ferrous stage, so as to prevent a detrimental corrosion of the 45 walls of the vessel and the evolution of hydrogen.

According to our present invention one can conveniently work with ammonia of 25 per cent strength or even of a lower percentage. 50 The reaction takes place between 150° C. and 250° C. the pressure varying from 30 to 60 atmospheres. The most favorable temperature of the reaction is 200° C to 210° C. Undesirable by-products such as β -naphthylamine and β -naphthol are not formed in considerable quantities.

The constitution of the new iron-compound is approximately as follows: $C_{11}H_7O_2NFe$. The product is yellow to brownish-black, according to the conditions of the reaction by which it has been formed; it is brownish-black if it has been prepared in the presence of iron in the ferrous stage, and yellow, if the presence of metallic iron has given occasion for a reduction by nascent hydrogen. 55 Apart from this coloration, there could not

be found any difference between the products of different appearance. They show the same insolubility in all solvent and the same chemical behaviour which they also manifest, as regards quantitative yields and properties, when transformed by decomposition into 2-aminonaphthalene-3-carboxylic acid. The decomposition of the iron compound is effected by heating for a prolonged time with 10 a concentrated or moderately diluted acid or alkali. This surprising reaction in which the iron compound is formed, does not consist in a catalytic action of the metal salt, but in the stoichiometric formation of an iron 15 compound with 1 atom of bivalent iron to 1 molecular proportion of amino acid. Both the results of analysis and the chemical properties of the new compound are at the present moment best explained by the probable 20 constitution

25

without warranting the absolute correctness of this formula. The product can certainly 30 not be regarded as being a simple iron salt of the aminonaphthalene carboxylic acid, for the normal iron salt of the 2-aminonaphthalene-3-carboxylic acid described by Möhlau in "Berichte der Deutschen Chemischen Ge- 35 sellschaft" volume 28 (1895), page 3097, contains only $\frac{1}{2}$ atom of bivalent iron to 1 molecular proportion of aminonaphthalene- 40 carboxylic acid and is immediately decomposed in the cold by dilute acids or alkalies, also by ammonia, whereas the iron compound obtainable according to our present invention, contains 1 atom of bivalent iron to 1 molecular proportion of aminonaphthalene- 45 carboxylic acid and can be decomposed only by a prolonged heating with strong acids or caustic alkalies, but not by ammonia nor in the cold. Ammonium 2-aminonaphthalene- 50 3-carbonate yields with ferrous salt the normal iron salt described by Möhlau, but by the addition of an excess of ammonia the latter is immediately re-decomposed into ammonium aminonaphthalene carbonate and ferrous hydroxide. When working, however, under pressure, there is obtained from aminonaphthalene carboxylic acid, ammonia and a ferrous salt a body which is similar to the compound above described and probably identical with it.

In the hitherto known reactions in the 60 main of the aminonaphthalene carboxylic acid there cannot be found an analogue to this iron compound.

The following examples illustrate our invention, but they are not intended to limit it thereto. The parts are by weight.

1. A mixture of 100 parts of 2-hydroxynaphthalene-3-carboxylic acid, 150 parts of iron vitriol and 600 parts of ammonia of 25 per cent strength is heated in an autoclave provided with a stirrer for 20-30 hours to 70 200° C. to 210° C. without having regard to the separation of ferrous hydroxide. During this operation the pressure rises to about 40 atmospheres.

After having distilled the ammonia, the 75 content of the vessel is filtered. The filtrate contains slight quantities of unaltered 2-hydroxynaphthalene-3-carboxylic acid.

The crystalline brownish-black mass remaining on the filter is the iron compound 80 of 2-aminonaphthalene-3-carboxylic acid. It contains small quantities of ferrous hydroxide which, if the compound is to be prepared in a pure state, can be eliminated by washing with cold dilute hydrochloric acid. In 85 order to obtain the free 2-aminonaphthalene-3-carboxylic acid, the crude iron compound (calculated upon 100 parts of starting 2-hydroxynaphthalene-3-carboxylic acid) is 90 boiled for about 2 hours with 1500 parts of moderately diluted hydrochloric acid (for instance in the proportion 1:4) and filtered hot. Only some charred substance remains 95 undissolved. The hydrochloride of 2-aminonaphthalene-3-carboxylic acid is salted out from the filtrate by means of common salt, filtered in the cold and washed with a saturated solution of common salt. The yield of 100 the hydrochloride amounts to 85 to 90 per cent of the theory.

2. 110 parts of sodium 2-hydroxynaphthalene-3-carboxylate, 100 parts of ferrous chloride, 500 parts of ammonia of 25 per cent strength and 500 parts of water are heated in a high-pressure autoclave for 24 hours to 105 200° C. to 210° C. The pressure amounts to about 35 atmospheres.

After blowing off the ammonia the 110 contents of the vessel is filtered. From the filtrate there can be separated by means of hydrochloric acid a small quantity of unaltered 2-hydroxy-naphthalene-3-carboxylic acid.

The separated insoluble iron compound is 115 boiled for 2 hours with 200 parts of caustic soda solution of 40° Bé. and 800 parts of water, then filtered hot and subsequently washed with hot water. The free 2-aminonaphthalene-3-carboxylic acid is precipitated in the filtrate by adding thereto hydrochloric acid until there is an acid reaction towards Congo paper and neutralizing the free hydrochloric acid by means of sodium acetate. The yellow acid is separated by pressing. The yield of 2-aminonaphthalene-3-carboxylic acid amounts to 85 to 90 per cent of the theory.

3. 100 parts of 2-hydroxynaphthalene-3-carboxylic acid, 80 parts of iron turnings, 80 parts of ammonium chloride, 500 parts of ammonia of 25 per cent strength are heated, 120

while stirring for 24 hours to 180° C. to 190° C. in an autoclave lined with stones. The pressure amounts to 40 to 45 atmospheres.

After having blown off the ammonia and the hydrogen which has been formed, the contents of the vessel is filtered. The filtrate contains small quantities of 2-hydronaphthalene-3-carboxylic acid.

The isolated yellow iron compound of the 10 2-aminonaphthalene-3-carboxylic acid, after being freed in a mechanical way as far as possible from the iron which has not entered into reaction, is mixed, while stirring, with 700 parts of concentrated hydrochloric acid; 15 the whole is heated to boiling, while well stirring, by passing steam through it, the boiling is continued for a quarter of an hour and the mass is then stirred in the cold. It is filtered while cold and washed with a saturated 20 solution of common salt in order to eliminate therefrom the iron salt which has been formed during the decomposition process. The yield of the hydrochloride amounts to 85 to 90 per cent of the theory.

25 It is expressly stated that when working according to Example 3 it is dangerous to use an iron autoclave without stonelining because not only the iron which is added but also the iron of the wall of the vessel is strongly 30 attacked by the action of the chlorine ions. After a number of operations the destruction of the iron vessel and the danger of an explosion would be inevitable. The working methods according to Examples 1 and 2, however, allow to use an ordinary iron autoclave without there being any danger. Long experience has proved that there is in this case no corrosion of the walls of the vessel.

The different working methods described 35 in the preceding examples may, of course, be largely varied and combined.

In the following claims the term "an agent capable of yielding bivalent iron ions" is intended to comprise salts of the bivalent iron or mixtures which are capable of yielding salts of the bivalent iron in the presence of ammonia, such as for instance a mixture of metallic iron and ammonium chloride, or the like.

40 We claim:

1. The process of preparing 2-aminonaphthalene-3-carboxylic acid by producing the insoluble complex iron compound of the probable formula:

45 and decomposing this compound, so as to form 2-aminonaphthalene-3-carboxylic acid.

50 2. The process of preparing 2-aminonaph-

thalene-3-carboxylic acid by heating a compound of the following formula:

76

wherein X stands for hydrogen or an alkali metal, with ammonia in a closed vessel in the presence of an agent capable of yielding bivalent iron ions and decomposing the insoluble complex iron compound thus obtained of the probable formula:

76

76

so as to form 2-aminonaphthalene-3-carboxylic acid.

3. The process of preparing 2-aminonaphthalene-3-carboxylic acid by heating 2-hydronaphthalene-3-carboxylic acid with ammonia in a closed vessel in the presence of an agent capable of yielding bivalent iron ions and decomposing the insoluble complex iron compound thus obtained of the probable formula:

90

so as to form 2-aminonaphthalene-3-carboxylic acid.

4. The process of preparing 2-aminonaphthalene-3-carboxylic acid by heating 2-hydronaphthalene-3-carboxylic acid with ammonia in a closed vessel in the presence of a ferrous salt and decomposing the insoluble complex iron compound thus obtained of the probable formula:

105

so as to form 2-aminonaphthalene-3-carboxylic acid.

5. The process of preparing 2-aminonaphthalene-3-carboxylic acid by heating 2-hydronaphthalene-3-carboxylic acid with ammonia in a closed vessel in the presence of ferrous sulfate and decomposing the insoluble complex iron compound thus obtained of the probable formula:

120

120

120

130

130

so as to form 2-aminonaphthalene-3-carboxylic acid.

6. The process of preparing 2-aminonaphthalene-3-carboxylic acid by heating 2-hydroxynaphthalene-3-carboxylic acid with ammonia in a closed vessel in the presence of an agent capable of yielding bivalent iron ions at a temperature between 150° C. and 250° C. and decomposing the insoluble complex iron compound thus obtained of the probable formula:

15

by treating it with a mineral acid in the heat.

7. The process of preparing 2-aminonaphthalene-3-carboxylic acid with ammonia in a closed vessel in the presence of a ferrous salt at a temperature between 150° C. and 250° C. and decomposing the insoluble complex iron compound thus obtained of the probable formula:

30

by treating it with a mineral acid in the heat.

8. The process of preparing 2-aminonaphthalene-3-carboxylic acid by heating 2-hydroxynaphthalene-3-carboxylic acid with ammonia in a closed vessel in the presence of ferrous sulfate at a temperature between 150° C. and 250° C. and decomposing the insoluble complex iron compound thus obtained of the probable formula:

45

by treating it with a mineral acid in the heat.

9. The process of preparing 2-aminonaphthalene-3-carboxylic acid by heating 2-hydroxynaphthalene-3-carboxylic acid with ammonia in a closed vessel in the presence of an agent capable of yielding bivalent iron ions at 200° C. to 210° C. and decomposing the insoluble complex iron compound thus obtained of the probable formula:

60

by treating it with a mineral acid in the heat.

10. The process of preparing 2-aminonaphthalene-3-carboxylic acid by heating 2-hydroxynaphthalene-3-carboxylic acid with

ammonia in a closed vessel in the presence of a ferrous salt at 200° C. to 210° C. and decomposing the insoluble complex iron compound thus obtained of the probable formula:

75

80

by treating it with a mineral acid in the heat.

11. The process of preparing 2-aminonaphthalene-3-carboxylic acid by heating 2-hydroxynaphthalene-3-carboxylic acid with ammonia in a closed vessel in the presence of ferrous sulfate at 200° C. to 210° C. and decomposing the insoluble complex iron compound thus obtained of the probable formula:

85

90

by treating it with a mineral acid in the heat.

12. The process of preparing 2-aminonaphthalene-3-carboxylic acid by heating 2-hydroxynaphthalene-3-carboxylic acid with ammonia of 25 per cent strength in an autoclave provided with a stirrer in the presence of ferrous sulfate for about 24 hours to 200° C. to 210° C. and transforming the insoluble complex iron compound thus obtained having the probable formula:

100

105

110

if required after having it purified, into the 2-aminonaphthalene-3-carboxylic acid by boiling it for about 2 hours with dilute hydrochloric acid (1:4).

115

13. As a new product the compound of the probable constitution:

125

said product being a crystalline compound which, when heated for some time with a concentrated or moderately diluted acid or caustic alkali solution is transformed by decomposition into 2-aminonaphthalene-3-carboxylic acid.

130

In testimony whereof, we affix our signatures.
